UNITED STATES PATENT OFFICE

HENRY T. BUSSMANN, OF ST. LOUIS, MISSOURI

ELECTRIC FUSE

Application filed November 10, 1924. Serial No. 749,075.

The object of my invention is to provide a link that will operate safely, possess desirable short-circuit characteristics and afford a practical and efficient time lag.

5 This application was filed at the same time as my application No. 749,074 and embodies a constructional detail thereof.

In the drawings, Fig. 1 shows a fuse link and Fig. 2 shows my invention applied to 10 an enclosed fuse.

In the drawings, 3 shows terminal members which may be of any suitable material. 4 is a member which in the operation of the fuse is not designed to melt. This member 15 is made of a comparatively low resistance material, such as copper, which because of its high current carrying capacity relative to other parts of the link makes this member essentially non-fusing.

20 5 shows fusing members of the link connected to the member 4 at the points 6. These fusing members need not be integral with the terminal members and may be of any suitable cross-sectional area. They are 25 made of any material of relatively low melting point, such as zinc, lead, tin, or other similar material.

The fusing members are made of short 30 length relative to the member 4 and in the use of my invention I prefer to make this fusing section as short as is consistent with the securing of desirable short-circuit characteristics. For example in 250 and 600 volt 35 links the fusing sections I prefer to make approximately $\frac{1}{8}$ of an inch in length.

By my invention I obtain whatever advantages there are in the use of a high melting point material for fuse purposes without 40 its disadvantages, and I obtain a practical and commercially efficient time lag without increasing the volume of metal that must be volatilized when the fuse is blown on heavy short circuits.

45 In describing the arrangements employed and shown in the drawings hereto attached and described in the specification, I do not limit my invention to the precise form, shape or construction shown, or to the several parts 50 thereto, inasmuch as various alterations may

be made without changing the scope of my invention.

I claim:

1. A fuse link having a relatively long non-fusing member and a plurality of relatively short fusing members, the non-fusing member having a higher melting point than that of a fusing member. 55

2. A fuse link adapted to be used in a standard size casing having a relatively long non-fusing member of relatively high melting point and a plurality of relatively short fusing members of a lower melting point. 60

3. An enclosed fuse having a casing, terminals therefor; a link having a relatively long member of relatively high melting point and a plurality of relatively short fusing portions of relatively low melting point. 65

4. The combination of a casing, terminals 70 therefor, a fuse link connected to said terminals, said fuse link having a relatively long central member and a plurality of relatively short members, the short members having a lower melting point than that of 75 the central member.

HENRY T. BUSSMANN.
